COUNTER USING BEAM SWITCHING TUBE WITH
MEANS FOR DISABLING CARRY SIGNAL GEN-
ERATING MEANS DURING RESTArpad Somlyody, Raritan, N.J., assignor to Burroughs
Corporation, Detroit, Mich., a corporation of Michigan

Filed Nov. 19, 1962, Ser. No. 238,475

7 Claims. (Cl. 315—8.5)

This invention relates to electronic counting circuits and particularly to counting circuits using multi-position magnetron beam switching tubes as the counting elements thereof.

Magnetron beam switching tubes are counting devices which include an electron-emitting cathode and ten groups of electrodes, each of which is adapted to receive an electron beam from the cathode and to provide an output signal therefrom. Each group of electrodes includes a target electrode which receives an electron beam and produces an output signal therefrom, an auxiliary collector electrode, a spade electrode which forms and holds an electron beam on its associated target electrode, and a switching electrode which may be used to switch an electron beam from one group of electrodes to the next to perform the counting operation.

In the operation of magnetron beam switching tubes in counter circuits, a typical multi-stage counter includes a plurality of such tubes connected together in series. Each tube is adapted to perform a counting cycle in which an electron beam switches from position to position, and, when a predetermined last position is reached in a tube, a carry pulse is transmitted to the next tube in the counting chain. Under some circumstances, the carry operation is accompanied by the clearing and resetting of an electron beam in a tube which has just completed a counting cycle. In arranging the circuitry to perform the beam clearing and resetting operation and the signal carry operation, problems generally arise due to the fact that consideration must be given to obtaining an output pulse from the same position from which the carry pulse is generated. In general, it is necessary to prevent the reset pulse itself from operating as a signal carry pulse.

Accordingly, the principles and objects of the present invention are concerned with the provision of an improved counter using magnetron beam switching tubes as the counting units thereof, and having improved circuit means for obtaining a carry signal and for clearing and resetting an electron beam in each tube.

Briefly, a counting circuit embodying the invention includes a multiposition beam switching tube as the counting element(s) thereof, with one of the positions of the tube being selected both for the transmission of a carry pulse at the end of a counting cycle and for the resetting of an electron beam after a beam has been cleared and it is desired to initiate a new counting cycle. A signal generating means is coupled to said one position for generating a carry pulse when an electron beam registers a count in said one position, and auxiliary means is coupled to said signal generating means for disabling said signal generating means during the beam resetting operation.

In the drawing, the single figure is a schematic representation of a circuit embodying the invention.

The circuit shown in the drawing is particularly suited for use with magnetron beam switching tubes such as the type 6700 tube and with similar devices sold by the Burrough Corporation and known as Beam-X switches. These devices are cylindrical in form, but they are shown schematically in linear form as tube 10 in FIG. 1. The tube 10 has an envelope 12 which contains a central cathode 14 and ten groups of electrodes spaced radially equidistantly from and surrounding the cathode. For

2

simplicity, only five groups of electrodes are shown numbered "1," "2," . . . "8," "9," and "0." Each group of electrodes includes a spade electrode 16 and a target electrode 18, with each spade electrode serving to form and hold an electron beam on its corresponding target electrode which itself provides an output signal from the beam. A switching electrode 20, known as a switching grid and used for switching an electron beam from position to position, is also included in each group of electrodes. In the Beam-X switch, an auxiliary electrode 22 is provided between each target and the adjacent leading spade, and the auxiliary electrode acts as a current collecting electrode.

The tube 10 also includes suitable means (not shown) for providing an axial magnetic field which operates with electric fields within the tube to form an electron beam and switch it from one group of electrodes to the next. Such means may be an external permanent magnet or internal magnets or the like. The direction in which an electron beam is urged, that is clockwise or counter-clockwise, is called the leading direction, and is always the same and is determined by the orientation of the electric and magnetic fields.

In the circuit of the drawing, each of the spade electrodes 16 except the "0" position spade is coupled through a spade load resistor 26 to a bus 28, one end of which is connected to a source of reference potential such as ground. The same spades are also coupled through separate resistors 32 to ground. It is assumed that the "0" position is the one at which an electron beam is to be reset and from which a carry pulse is generated. The circuit connections of the "0" spade are described below.

The target electrodes 18 and connected through suitable load resistors 32 to the bus 28. In addition, an auxiliary output tap 34 is provided at each target for connection to a suitable utilization device or circuit, for example, the glow cathodes of a 6844A indicator tube, or a printing mechanism or the like.

The switching grid electrodes 20 are connected to a source of counting pulses, and, in one arrangement, the grids at the even-numbered positions are connected together in one set and the grids at the odd-numbered positions are connected together in another set. Each set of grids is then connected to one of the outputs of a suitable flip-flop circuit 42 which comprises a source of counting pulses.

According to the invention, an electron discharge device is provided for generating a carry pulse for transmission for tube 10 to the next counting tube (not shown). One suitable device is a PNP transistor 50 which includes base, emitter, and collector electrodes 54, 55, and 56, respectively. The base electrode of the transistor 50 is connected through spade resistor 26' to the "0" spade, and the emitter electrode 55 is connected to bus 28. A diode 60, oriented as shown for controlling the transistor base potential, is connected between the emitter 55 and base 54 of transistor 50. The base electrode is also coupled through a suitable resistor 64 to a source of positive D.C. bias potential V_b of the order of 12 volts. The collector electrode 56 is provided with an output terminal 68, from which a carry pulse is transmitted, and it is also coupled through a load resistor 70 and a resistor 71 to the cathode 14 of the beam switching tube. The junction point 74 of resistors 70 and 71 is connected through a parallel resistor 78-capacitor 80 network to ground. Resistors 71 and 78 comprise a bleeder network. The "0" spade is also coupled through a capacitor 90 to cathode 14 of counting tube 10.

A source 94 of positive reset pulses is coupled to the cathode 14 of tube 10, and a negative D.C. power source V_c is coupled through source 94 to cathode 14. The

potential of V_c may be about -55 volts which is selected to provide about -12 volts at point 74.

In operation of the circuit of the invention, initially, with no current flowing to the "0" spade and to the base of transistor 50, the transistor is held "off." Point 74 is at about -12 volts, and capacitor 80 is charged to the potential of point 74. The collector 68 is also at about -12 volts. As beam switching tube 10 executes a counting cycle under the influence of counting pulses applied alternately to the two sets of switching electrodes 20 by flip-flop 42, an electron beam moves from position to position in the tube. As the beam flows to each position, an output signal appears at tap 34 of each target electrode. When the beam reaches the last position in the counting cycle, the "9" position, a normal output signal is provided, and, when the next switching pulse applied to the switching grids causes the beam to move to the "0" position, the starting position of the next counting cycle, the spade electrode at the "0" position receives beam current and drops in potential. This lowered potential applied to the base of the transistor 50 causes the transistor to be turned on, and a positive carry pulse appears at the collector output terminal 68 which rises to about ground potential. This positive pulse is used to drive the next counting tube in the counting chain which thus registers an indication of the fact that the first tube has completed its counting cycle. When the tube 10 executes another counting cycle, a carry pulse is applied to and is registered in the next tube. Generally, the positive carry pulse would be applied to a flip-flop (not shown) similar to flip-flop 42.

When it is desired to clear an electron beam in tube 10 and reset it at the "0" position, a generally sawtooth wave 95 is applied from source 94 to the cathode 14, and the positive portion thereof raises the cathode to a level at 35 which an electron beam in the tube is cleared. In this case, the cathode is raised to about ground potential to cause the beam to clear. The negative portion of wave 95 is then coupled through capacitor 90 to the "0" spade, and the beam is then reformed in the "0" position. It is noted that the negative portion of wave 95 is also coupled to the base electrode of transistor 50 which might thus be turned on and caused to generate a spurious carry pulse. However, transistor 50 is prevented from being turned on by the fact, that, when wave 95 raises the cathode to ground potential, the capacitor 80 discharges and point 74 and the collector 56 go to ground potential. With the supply voltage thus removed from the transistor, it is prevented from being turned on and generating an output carry pulse when the negative portion of the wave 95 is applied through capacitor 90 to the "0" spade electrode to set a beam at the "0" position.

What is claimed is:

1. A counter circuit including an electron beam switching tube having a cathode and a plurality of groups of electrodes; each group including a target electrode which receives an electron beam and produces an output signal therefrom, a spade electrode which holds an electron beam on its associated target electrode, and a switching electrode which serves to switch an electron beam from one group of electrodes to the next;

said cathode being connected to a source of reference potential, said spade electrodes being connected through resistive paths to a source of reference potential, said target electrodes being coupled through resistive paths to a source of reference potential, and said switching electrodes being connected to a source of switching signals;

one of the positions being selected both for the transmission of a carry pulse at the end of a counting cycle and for the resetting of an electron beam after a beam has been cleared and it is desired to initiate a new counting cycle;

signal generating means coupled to said one position

for generating a carry pulse when an electron beam registers a count in said one position; and means coupled to said signal generating means for disabling said signal generating means during a pulse resetting operation.

2. A counter circuit including an electron beam switching tube having a cathode and a plurality of groups of electrodes; each group including a target electrode which receives an electron beam and produces an output signal therefrom, a spade electrode which holds an electron beam on its associated target electrode, and a switching electrode which serves to switch an electron beam from one group of electrodes to the next;

said cathode being connected to a source of reference potential, said spade electrodes being connected through resistive paths to a source of reference potential, said target electrodes being coupled through resistive paths to a source of reference potential, and said switching electrodes being connected to a source of switching signals;

one of the positions being selected both for the transmission of a carry pulse at the end of a counting cycle and for the resetting of an electron beam after a beam has been cleared and it is desired to initiate a new counting cycle;

an electron discharge device coupled to said one position for generating a carry pulse when an electron beam registers a count in said one position;

a pulse source coupled both to the cathode of said beam switching tube and to said one position in said tube for clearing and resetting an electron beam in said tube;

and disabling means coupled to said discharge device for disabling it and thus preventing it from generating a carry pulse during a pulse resetting operation.

3. The circuit defined in claim 2 wherein said discharge device is a transistor having base, emitter, and collector electrodes,

the base electrode of said transistor being coupled to the spade electrode at said one position in said tube, the emitter electrode being coupled to a source of reference potential, the collector electrode being coupled through a resistive path to the cathode of said beam switching tube,

said pulse source also being coupled to the spade electrode at said one position, said disabling means being coupled to the cathode of said tube so that when a pulse is applied to said cathode to clear a beam in said tube, said disabling means operates to disable said transistor and prevent it from operating when a pulse is applied to said spade electrode at said one position to cause an electron beam to form thereof.

4. The circuit defined in claim 2 wherein said discharge device is a transistor having base, emitter, and collector electrodes, and including a bleeder network coupled from said cathode to a reference potential,

the collector electrode of said transistor being coupled to a point on said bleeder network whereby an operating potential is applied thereto, the emitter electrode of said transistor being coupled to a source of reference potential, and the base electrode being coupled to the spade electrode at said one position in said tube,

said disabling means being operatively related to said bleeder network whereby it can affect said operating potential of said collector and can disable said transistor.

5. The circuit defined in claim 2 wherein said discharge device is a transistor having base, emitter, and collector electrodes, and including a bleeder network coupled from said cathode to a reference potential,

said emitter electrode being coupled to a source of reference potential, said base electrode being coupled

to the spade electrode at said one position in said tube,
 a capacitor coupled to a portion of said bleeder network and comprising a portion of said disabling means, the collector electrode of said transistor being coupled to a point on said bleeder network whereby an operating potential is applied thereto,
 said capacitor controlling the potential of said point and of said collector electrode whereby the operation of said transistor is controlled.

6. The circuit defined in claim 2 wherein said discharge device is a transistor having base, emitter, and collector electrodes, and including a bleeder network coupled from said cathode to a reference potential,
 said emitter electrode being coupled to a source of reference potential, said base electrode being coupled to the spade electrode at said one position in said tube,
 a capacitor coupled to a portion of said bleeder network and comprising a portion of said disabling means,
 the collector electrode of said transistor being coupled to a point on said bleeder network whereby an operating potential is applied thereto,
 said capacitor controlling the potential of said point and of said collector electrode whereby the operation of said transistor is controlled, and a pulse source coupled to the switching electrodes in said

10

25

tube for applying counting pulses thereto and causing an electron beam to switch from position to position therein.

7. The circuit defined in claim 2 wherein said discharge device is a transistor having base, emitter, and collector electrodes, and including a bleeder network coupled from said cathode to a reference potential,
 said emitter electrode being coupled to a source of reference potential, said base electrode being coupled to the spade electrode at said one position in said tube,
 a capacitor coupled to a portion of said bleeder network and comprising a portion of said disabling means,
 the collector electrode of said transistor being coupled to a point on said bleeder network whereby an operating potential is applied thereto,
 said capacitor being charged to an operating potential while said tube performs a counting operation, said capacitor being discharged when a beam is cleared and reset in said tube,
 said capacitor thus controlling the potential of said point and of said collector electrode whereby the operation of said transistor is controlled.
